211,635

FISHING POLE HOLDER

John W. Holm, P.O. Box 522, Willmar, Minn. 56201

Filed Mar. 16, 1967, Ser. No. 6,265

Term of patent 14 years

(Cl. D22—22)

FIG 1

FIG 6

FIG 2

FIG 7

FIG 3

FIG 4

FIG 5

FIG 8

FIG 13

FIG 9

FIG 14

FIG 10

FIG 11

FIG 12

FIG. 1 is a perspective view of a fishing pole holder showing my new design;

FIG. 2 is a front elevation thereof;

FIG. 3 is a rear elevation thereof;

FIG. 4 is a top plan view thereof;

FIG. 5 is a bottom plan view thereof;

FIG. 6 is a front end elevation thereof;

FIG. 7 is a rear end elevation thereof;

FIG. 8 is a perspective view of a modified embodiment of the fishing pole holder shown in FIG. 1;

FIG. 9 is a front elevation thereof;

FIG. 10 is a rear view thereof;

FIG. 11 is a top plan view thereof;

FIG. 12 is a bottom plan view thereof;

FIG. 13 is a front end elevation thereof; and

FIG. 14 is a rear end elevation thereof.

The broken lines are shown for illustrative purposes only.

I claim:

The ornamental design for a fishing pole holder, as shown and described.
